CLAIM

The ornamental design for a support apparatus, as shown
and described.

DESCRIPTION

FIG. 1 is a front, left side, overhead perspective view of a
support apparatus.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The evenly broken lines in the drawings show portions of the
support apparatus that form no part of the claimed design.
The dot-dash lines represent boundaries of the claim and
form no part thereof.

1 Claim, 7 Drawing Sheets
